WIRE CLOTH TUBE FORMING MACHINE

James J. Harmon, Jr., Clayton, Mo., assignor to
 Ludlow-Saylor Wire Co., St. Louis, Mo., a corporation of Missouri

Application December 4, 1950, Serial No. 199,069

16 Claims. (Cl. 219—6)

1

The present invention relates generally to machines for forming wire cloth, and more particularly to a novel machine by which wire cloth is automatically formed into seam-welded tubes of predetermined length and diameter.

In brief, the present novel wire cloth tube forming machine includes mechanism for receiving a continuous strip of wire cloth, forming it into a continuous tube, seam-welding the tube thus formed and severing the thus formed and welded tube into segments of predetermined lengths. Actuating and correlating electrical and pneumatic equipment forms part of the present machine. The machine cooperates with a spot welder of well known type in the welding operation and attains a high speed of production of welded tube segments.

An object of the present invention is to provide a novel automatic machine which functions to transform a continuous strip of wire cloth into a continuous wire cloth tube at a high rate of speed.

Another object is to provide a novel automatic machine for producing wire cloth tubes of predetermined length and diameter at a high rate of speed.

Another object is to provide a novel wire cloth tube forming machine which is adapted to cooperate in automatic sequence with a conventional spot welder to produce a continuous seam-welded wire cloth tube.

Another object is to provide a novel wire cloth tube forming machine which may be adjusted to produce seam-welded wire cloth tubes of any desired length.

Another object is to provide a novel automatic wire cloth tube forming machine in which parts may be interchanged to provide for the production of wire cloth tubes of various diameters.

Another object is to provide a method for transforming a continuous strip of wire cloth into tubular segments of predetermined length.

Other objects are to provide a novel wire cloth tube forming machine for automatically producing wire cloth tubes of predetermined measurements which is sturdy in construction, which may be readily handled by operating personnel in an efficient manner with minimum instruction, which is adapted to maintain its high rate of production of wire cloth tubes for long periods

2

of time under continuous use with normal maintenance, and which is otherwise adapted to fulfill the objects and advantages sought therefor.

5 The foregoing and other objects and advantages are apparent from the following description taken with the accompanying drawings, in which:

Fig. 1 is a plan view of a wire cloth tube forming machine constructed in accordance with the 10 teachings of the present invention, electric wiring and some air hose connections being omitted for purposes of clarity;

Fig. 2 is a side elevational view thereof;

Fig. 3 is an end elevational view thereof, showing 15 fragmentarily in dotted lines a conventional spot welder on which the machine may be mounted and with which it cooperates;

Fig. 4 is a vertical longitudinal cross-sectional view on substantially the line 4—4 of Fig. 1, the 20 wire cloth reel being omitted for conservation of space;

Fig. 5 is a vertical transverse cross-sectional view on substantially the line 5—5 of Fig. 1;

Fig. 6 is a vertical transverse cross-sectional 25 view on substantially the line 6—6 of Fig. 1;

Fig. 7 is a vertical transverse cross-sectional view on substantially the line 7—7 of Fig. 1;

Fig. 8 is a vertical longitudinal cross-sectional view on substantially the line 8—8 of Fig. 1;

30 Fig. 9 is an enlarged fragmentary cross-sectional view of a portion of a tube holder at the cut-off end;

Fig. 10 is an enlarged vertical transverse cross-sectional view through an electrode showing its 35 internal water cooling construction, an integral lug being shown fragmentarily in elevation;

Fig. 11 is an enlarged view of a segment of a 40 continuous wire cloth strip illustrating the manner in which the strip is formed into a continuous cylinder;

Fig. 12 is a side elevational view of the wire cloth segment shown in Fig. 11;

Fig. 13 is a plan view of a wire cloth tube formed by the present machine;

45 Fig. 14 is an enlarged vertical transverse cross-sectional view on substantially the line 14—14 of Fig. 13;

Fig. 15 is a wiring diagram illustrating the electrical equipment forming part of the actuating mechanism of the present machine; and

Fig. 16 is a diagrammatic layout of the pneumatic equipment forming part of the operating mechanism of the present machine.

Referring to the drawings more particularly by the numerals thereon, the wire cloth tube forming machine shown generally as 10 includes a reel assembly 11 so mounted as to feed a continuous strip 12 of wire cloth to an internal electrode assembly 13 substantially enclosed within a former assembly 14. The strip 12, after being formed into a continuous tube in a manner to be described, is advanced (to the right in the views of Figs. 1 and 2) by a slide and clamp assembly 15, and a portion of the tube is subsequently cut off by the action of a saw assembly 16. All of the above identified assemblies are mounted upon a base 17 secured by bolts 18 to a bracket 19. The bracket 19, shown dotted in Figs. 2 and 3, is appropriately secured to a frame member 20 of an electric welding apparatus 21, as shown in Fig. 3.

The reel assembly 11 includes a bracket 25 appropriately formed from angle iron and secured as by a bolt 26 to a horizontal plate element 27 of the base 17. Near the end of an upwardly extending arm 28 of the bracket 25, a bolt and nut assembly 29 supports a spacing washer 30 and two reel sides 31 which are separated by a sleeve 32 to form a reel upon which a spool of wire cloth may be mounted so as to permit the drawing off of a continuous strip 12 therefrom.

Fig. 10 shows the internal electrode assembly 13, which includes an electrode 35 having a cylindrical portion 36 and a flared portion 37. This electrode 35, which is preferably made of copper, has a longitudinal hole 38 into the end of which is threaded an adapter 39. The adapter 39 has an axial bore 40 extending from its threaded end to a point 41, the diameter of the bore 40 being substantially equal to that of the hole 38 in the electrode 35. Beyond the point 41 to the left, as shown in Fig. 10, is a coaxial extension 42 of the bore 40, said coaxial extension 42 being smaller in diameter than the bore 40 and threaded to receive a tube 43, which extends from its threaded engagement with the adapter 39 concentrically through the bore 40 and substantially to the blind end of the hole 38 in the electrode 35. An orifice tube, such as 44 in Fig. 10, may be secured as by welding into the unthreaded end of the tube 43. The purpose of this internal construction is to provide cooling means for the electrode 35, it being understood that water or other cooling medium may be introduced into the adapter through a connection 45 which threadedly receives a nipple 23 making connection with a coolant tube 24, the water being required thereafter to traverse the length of the tube 43 on the inside thereof to return along the outside thereof in the space between the tube 43 and the wall of the hole 38 and the bore 40 to emerge from the adapter 39 through a connection 46 which threadedly receives a nipple 33 making connection with a coolant tube 34.

A lug 48 is formed integrally with the electrode 35 to extend upwardly therefrom as shown in Fig. 10. This lug 48 is substantially rectangular in shape and has a width substantially equal to the diameter of the cylindrical portion 36 of the electrode 35. At its forward edge, which is to the right in Fig. 10, the lug 48 has a notch 49 on each side thereof to form a wedge-shaped edge 50 as best shown in Fig. 1.

A tube guide extension rod 51 having a flange 75

52 equal in diameter to the cylindrical portion 36 of the electrode 35 is secured as by threaded engagement to the end of the electrode 35 to extend coaxially therefrom. A sleeve 53 and a compression spring 54 are slidably mounted upon the guide extension rod 51 and are retained thereon by a collar 55 in threaded engagement with the free end of the guide extension rod 51. The outside diameter of the sleeve 53 and of the 10 collar 55 are both substantially equal to the outside diameter of the cylindrical portion 36 of the electrode 35 and the maximum diameter of the spring 54 when fully compressed is also no greater than the diameter of this cylindrical portion 36 of the electrode 35. It may thus be seen that a tube formed to the outside diameter of the cylindrical portion 36 of the electrode 35 may be advanced from the said cylindrical portion 36 to and beyond the collar 55.

15 The internal electrode assembly 13 is mounted in and supported by the former assembly 14 which includes a cylindrical-shaped body 60 having a bore 61 shaped similarly to the outside of the cylindrical portion 36 and the flared portion 37 of the electrode 35 so as to leave a uniform annular space 62 between the outside of the electrode 35 and the inside of the bore 61. The body 60 has a slot 63 surmounted by two parallel rectangular lugs 64 into which slot 63 and between which lugs 64 the lug 48 of the electrode 35 is 20 removably secured as by a bolt and nut assembly 22 and locating pins 47, the latter being to maintain appropriate uniformity of the annular space 62. At its forward end, which is to the right in Fig. 1, the body 60 has a portion of its cylindrical outside surface cut down to form a flat area 65 having a longitudinal slot 66, the sides of which are tapered as shown in Fig. 7. The former assembly 14 is supported by two 25 strips 67 engaging slots 68 in opposite sides of the cylindrical body 60. The strips 67 are secured as by bolts 69 to upstanding sides 70 of the base 17.

30 A double acting cylinder assembly 75 is disposed horizontally between and parallel to the upstanding sides 70 of the base 17 and is supported by means of brackets 76 secured to the base element 27 by means of bolts 77. The cylinder assembly 75 includes a piston rod 78 adjustably attached by means of nuts 74 to a carrier assembly 79 of the slide and clamp assembly 15. The carrier 79 includes a horizontal plate 80, a vertical web 81, and two gussets 82, all in welded assembly as best shown in Figs. 4 and 5. Two 35 parallel strips 83 having transversely extending portions 84 are secured to the underneath side of the plate 80 so as slidably to engage the transversely extending portions 85 of two parallel strips 86 secured to the upper edges of the upstanding sides 70 of the base 17. The construction of this carrier 79, as best shown in Fig. 5, is seen to permit the longitudinal movement of the carrier 79 with respect to the cylinder assembly 75 by which it is actuated.

40 On the upper face of the plate 80 of the carrier 79 are mounted so as to oppose each other two identical clamp assemblies 90. Each clamp assembly 90 includes a single acting spring return cylinder assembly 91 secured to the plate 80 by bolts 92. Piston rods 93 having intermediate flanges 94 and end flanges 95 to which are secured, as by welding, channel elements 96 containing formed cushions 97 of resilient material, such as rubber, all as shown in Fig. 5, coat one 45 with the other to provide a clamping action be-

tween the formed faces of the cushions 97 and the outside of the aforementioned sleeve 53. Lower flanges 99 of the channels 96 rest slidably upon the upper face of the plate 80 so as accurately to dispose the formed faces of the cushions 97 in proper relation to the sleeve 53.

The cylinders 91 are air operated to provide movement of the piston rods 93 toward each other and are provided with an internal spring, which, upon release of air pressure within the cylinder, causes the piston rods 93 to retract until the intermediate flanges 94 abut the projections 100 of the cylinder assemblies 91. Quick exhaust valves 101 are connected with the cylinder assemblies 91 by means of bushings 102 and nipples 103. The quick exhaust valves 101 receive compressed air from air hoses 104 connected with the exhaust valve 101 by means of street elbows 105.

The saw assembly 16 includes an air motor 110 which rotates a spindle 111 to which is secured, as by a nut 112 and washers 108 and 109, a circular thin bladed saw 113. The motor 110 is supported in a suitable bracket 120 adjustably mounted upon a plate 121. The plate 121 is, in turn, appropriately secured to a slide 122 having a longitudinal T-slot 123 disposed parallel to the plane of rotation of the saw 113 and slidably engaging parallel strips 124 appropriately secured to a bed plate 125. The bed plate 125 is secured, as by welding, to horizontally disposed flanges 126 of angles 127 supported from the sides of the upstanding members 70 of the base 17, being secured thereto by bolts 128.

The saw assembly 16 is caused to move in horizontal translatory movement parallel to the plane of rotation of the saw 113 by a double-acting air operated cylinder assembly 135. A piston rod 136 of the cylinder assembly 135 is attached by means of a clevis 137 to a lug 138 projecting from the support 120. The cylinder assembly 135 is appropriately secured near one end of the bed plate 125 and is actuated by compressed air received from air hoses 140 and 141 at speeds adjustably controlled by speed valves 142 and 143 connected with the cylinder assembly 135 by nipples 144 and bushings 145. The connection of the air hoses 140 and 141 to the speed valves 142 and 143 is by means of check unit connecting assemblies 146, bushings 147, nipples 148 and street elbows 149.

A guard, such as 150, may be provided and appropriately mounted upon the transverse flange 126 of one of the angles 128 to serve as protection against the rotating saw 113.

A cut-off end tube holder 155 includes in welded assembly an angle member 156 appropriately secured to the horizontally disposed flange 126 of one of the members 127 and a second angle member 157 attached to an upstanding leg 158 of the angle member 156 so as to dispose in horizontal position a flange 159 of the angle member 157. Also included in the welded assembly 155 is a sleeve 160 secured to the vertical end edge of the horizontal flange 159. This sleeve 160 is disposed concentrically with the collar 55 so as to leave an annular space 161 therebetween. One end of the sleeve 160 coincides with the plane of the end of the collar 55 and also with the near edge of a slot 162 in the horizontal flange 159, as shown in Figs. 1 and 4. A sleeve segment 163 having a radius identical with that of the sleeve 160, but extending through an arc of only approximately 90° is also attached to the vertical edge of the horizontal flange 159 adjacent to the side of the slot 162 opposite that which coincides with the

end of the sleeve 160. The sleeve segment 163 has the center of its arc in axial extension to the center axis of the sleeve 160. It will be seen, then, that the saw 113 may be admitted past the forward end of the sleeve 160 into the slot 162, these elements cooperating to provide an efficient cut-off means to sever predetermined lengths of the wire cloth cylinder as such lengths are attained beyond the end of the sleeve 160.

10 A compressed air supply is conveyed to the slide and clamp assembly 15 by means of an air hose 170 connected by means of a check unit connecting assembly 171 to a nipple 172 engaging the stem portion of a T 173. One of the coaxial ends of the T 173 is connected to one of the air hoses 104 by means of a nipple 174 and an elbow 175. The other coaxial end of the T 173 is connected by means of a nipple 176, an elbow 177 and another nipple 178 to a coaxial end of a second T 179. The other coaxial end of the T 179 is connected to a nipple 180, in turn connected to an elbow 181, in turn connected to the other air hose 104. The stem portion of the T 179 is connected by means of a nipple 182, a sequence valve 183, and a second nipple 184 into the rear end of the cylinder assembly 75. The admission of air into the rear end of the cylinder assembly 75 causes the whole slide and clamp assembly 15 to move forward or to the right in the longitudinal views of the drawings. It may thus be seen that air from a single source, such as the air hose 170, actuates not only the clamp assemblies 90, but also the cylinder assembly 75 in its forward movement. The action of the sequence valve 183 is such as momentarily to delay the admission of air into the rear of the cylinder assembly 75 so that the forward translatory movement of the slide and clamp assembly 15 may be subsequent to the clamping action of the clamp assembly 90. When air pressure is released in the hose 170, the consequent reduction of pressure in the quick exhaust valves 101 permits the air in the cylinder assemblies 91 to be expelled directly to atmosphere through the quick exhaust valves 101, whereupon the piston rods 93 are retracted by the aforementioned spring means, thus quickly terminating the clamping action of the clamp assemblies 90. Compressed air to cause return movement of the slide and clamp assembly 15 is supplied through an air hose 190, a check unit connecting assembly 191, a nipple 192, a speed valve 193 and a second nipple 194 to the forward end of the cylinder assembly 75.

55 Fig. 16 shows in diagrammatic form an arrangement whereby compressed air may be distributed to the various power units of the pneumatically operated wire cloth tube forming machine. Thus, air from an air line 200 passes through a filter 201, a line 202, and thereafter divides to flow in one direction through a line 203, through a lubricator 204, through a line 205 to a grinder motor 206 which serves as the motor 110 in the saw assembly 16. From the line 202, air also flows through a line 207, through 60 a regulator and gauge assembly 208, through a line 209, through a lubricator 210, and through a line 211, whereupon it divides to flow through lines 212 and 213 to solenoid operated valves 214 and 215, respectively. The valve 214 controls the supply of air to the power units of the slide and clamp assembly 15. Thus, when the valve 214 is operated in one direction, air from the line 212 is conducted to a line 216 which corresponds to the air hose 170 as best shown in Fig. 1. While 65 the distribution of air from the air hose 170 has

70

been above described, the simple form of Fig. 16 shows a corresponding flow of air from the line 216 to divide and flow through lines 217 and 218, through the respective quick exhaust valves 101, through lines 221 and 222 to the respective cylinder assemblies 91. A portion of the air flowing through the line 218 is taken off by a line 223 and passed through the sequence valve 183, thence through a line 224 to the rear end of the double acting cylinder assembly 75. Operation of the valve 214 in the opposite direction causes air from the line 212 to be conducted by a line 225 to the forward end of the cylinder assembly 75.

The valve 215 controls the action of the double-acting cylinder assembly 135 which causes forward and return movement of the saw assembly 16. Thus, when operated in one direction, the valve 215 conducts air from the line 213 to a line 225 from which the air passes through the aforementioned speed control valve 143 and through a line 226 to one end of the double-acting cylinder assembly 135. In similar manner, operation of the valve 215 in the opposite direction conducts air from the line 213 to a line 227 from which it passes through the aforementioned speed control valve 142 and through a line 228 to the opposite end of the cylinder assembly 135.

The sequential operation of the various power units is automatically controlled by an arrangement of electrical circuits as shown in Fig. 15. The diagram of Fig. 15 shows five single pole, single throw, normally open micro switches, or the like, each of which is appropriately mounted to provide for its actuation in a predetermined sequence. Thus, a micro switch 240 is mounted so as to be actuated when the spot welder is in retracted position, a micro switch 241 is mounted so as to be actuated when the slide and clamp assembly 15 is in advanced position, a micro switch 242 is mounted so as to be actuated when the saw assembly 16 is in retracted position, a micro switch 243 is mounted so as to be actuated when the saw assembly 16 is in advanced position, and a micro switch 244 is adjustably mounted so as to be actuated when engaged by a finished portion of the wire cloth cylinder advanced from the machine 10. The switch 240 is supported by a bracket 239 mounted on a non-moving element of the welding apparatus 21 as shown in Fig. 3. Switches 241, 242, 243 and 244 are mounted directly on non-moving elements of the machine 10 and may be supported on appropriate brackets such as 245, 246, 247 and 248, respectively, as shown in Figs. 1-3.

The wire cloth tube forming machine above-described forms a continuous tube from a strip of wire cloth having predetermined appropriate width and mesh. The tube is formed generally in the manner indicated in Figs. 11 and 12 to have a substantially circular cross-section as shown in Fig. 14. Thus, a strip 12 of wire cloth is drawn from a reel assembly 11, as shown in Figs. 1 and 2 and is caused to pass longitudinally through the annulus 62 formed between the electrode 35 and the former body 60. While passing over the flared portion 37 of the electrode 35, the strip 12 is caused to assume an intermediate form as shown at 300 in Figs. 11 and 12. The wedge-shaped section 58 of the lug 43 permits edges 301 and 302 as shown in Fig. 11 to be brought together so that, when the cloth reaches the cylindrical portion 36 of the electrode 35, the edge 301 has lapped over the edge 302 as shown at 303. The passage of the strip 12 is not continuous through the machine, but occurs by stages as

effected by the slide and clamp assembly 15. The tube formed as above described emerges from the forward end of the former body 60 and passes over the flange 52 of the guide extension rod 51, over the sleeve 53, over the spring 54, and over the collar 55. The feeding action as effected by the slide and clamp assembly 15 results from the clamping action of the clamping assemblies 90 wherein the formed cushions 97 advance to compress the tube upon the sleeve 53 and the subsequent action of the cylinder assembly 75, whereby the whole clamping assembly 90 is caused to move in translatory movement, thereby causing a forward movement of the tube 304 as well as of the sleeve 53 against the action of the spring 54. When the slide and clamp assembly 15 has advanced to the forward end of its movement, the clamping action is released and the clamping assembly is returned to its original position, leaving the formed tube 304 in an advanced position. The sleeve 53 is returned by the action of the spring 54 to its original position abutting the flange 52.

Each time the formed tube 304 is brought forward as above described, an electrode 305 carried by a movable arm 306 of the welding apparatus 21 is caused to descend through the slot 66 to rest upon the overlapped edges 301 and 302 of the tube at 303. This action of the electrode 305 permits a welding current to flow therefrom through the overlapped edges 301 and 302 to the internal electrode 35, thus effecting a seam weld of the edges 301 and 302.

The formed and welded tube is thus seen to be advanced by stages until a predetermined length of finished tube such as 304 is brought to extend beyond the sleeve 160, whereupon the saw 113 advances to cut off the finished length.

As above mentioned, the wire cloth tube forming machine 10 operates under air power in co-operation with a conventional electric spot welder, the various movements being sequentially controlled by means of electrical circuits. Referring to Fig. 15, if it is assumed that the machine 10 is at rest with the slide and clamp assembly 15, the saw assembly 16, and the welder all in retracted position, then switches 241, 243, and 244 will each be open and switches 240 and 242 will each be closed. Now, if the 110-v. line is energized, two circuits will be completed, one through an actuating coil 251 of a single pole double throw latch relay 250 and the now closed switch 240 and another through the "retract" side of the solenoid valve 214 and through the normally closed contacts 252 of the relay 250. The latter circuit is, however, immediately opened by the action of the relay 250 in opening the contacts 252 and closing normally open contacts 253, which action now completes a circuit through these contacts 253, through the "advance" side of the valve 214, and through the now closed switch 242. The consequent advance of the slide and clamp assembly 15 thus constitutes the first mechanical response to the electrical control.

Arrival of the slide and clamp assembly 15 at the advanced end of its travel closes the switch 241 to complete a circuit through a coil 256 of a two pole, single throw, normally open relay 255. The closing of normally open contacts 257 of the relay 255 completes a circuit through an unlatching coil 254 of the relay 250 and the closing of normally open contacts 258 of the relay 255 completes a circuit through the welder. With respect to the former of these last-mentioned circuits, it will be noted that, inasmuch as the actu-

ating coil 251 of the relay 250 is still energized, the energization of the unlatching coil 254 will have no immediate switching effect. The energization of the welder circuit, however, has the effect of initiating a conventional automatic welding cycle wherein the welder (a welding electrode, to be more specific) is caused to advance, to complete the weld, and to retract in predetermined time sequence.

As soon as the welder leaves its retracted position, the switch 240 opens to deenergize the actuating coil 251 of the relay 250, and the still energized unlatching coil 254 permits opening of the contacts 253 and consequently of the circuit through the "advance" side of the valve 214. The latter action is, of course, followed instantly by closing of the contacts 252, once more to complete the circuit through the "retract" side of the valve 214, thus causing the slide and clamp assembly 15 to be retracted.

As soon as the slide and clamp assembly leaves its advanced position, the switch 241 opens to deenergize the coil 256 of the relay 255. The consequent opening of the contacts 257 and 258 opens the circuits through the unlatching coil 254 of the relay 250 and the circuit through the welder respectively. Deenergization of the unlatching coil 254 has no immediate effect since the relay 250 is already in its normal position, and the opening of the welder circuit does not affect completion of the timed welding cycle above described. With the arrival of the slide and clamp assembly 15 at the retracted end of its travel, it is obvious that further operation of the machine 10 must await the completion of the welding cycle as signified by the return of the welder to its retracted position. Upon such return, the switch 240 will again be closed and the above-described sequence of operation will be repeated again and again until the switch 244 is caused to close by engagement of the finished tube therewith.

Closing of the switch 244 completes a circuit through a coil 261 of a two pole, single throw, normally open relay 260, thus causing normally open contacts 262 and 263 to close and respectively to complete a circuit through the coil 256 of the relay 255 and a circuit through an actuating coil 266 of a two pole, single throw, normally open latch relay 265.

It is obvious that energization of the coil 256 of the relay 255 in this manner produces the same result as when it was energized through closing of the switch 241, i. e., it causes the welding cycle to be initiated and the unlatching coil 254 of the relay 250 to be energized. Initiation of the welding cycle, as previously described, causes the switch 240 to open the circuit through the actuating coil of the relay 250, thus opening the contacts 253 and closing the contacts 252 to reverse the valve 214, thereby to effect an immediate retraction of the slide and clamp assembly 15. It is thus apparent that the advance of the finished wire cloth tube may be halted at any point during the travel of the slide and clamp assembly 15 from its retracted position toward its advanced position in order to cut off a desired length of tube regardless of whether or not the desired length is a multiple of the normal travel of the slide and clamp assembly 15.

When the circuit through the actuating coil 266 of the relay 265 is completed as above mentioned, the normally open contacts 267 and 268 are caused to close and respectively to complete a circuit through the "advance" side of the solenoid valve

215 and a circuit through an unlatching coil 273 of a single pole, single throw, normally open latch relay 270. Completion of this circuit through the valve 215, of course, causes the saw assembly 16 to advance toward the now halted wire cloth tube to cut off a desired length thereof. Upon leaving its retracted position, the saw assembly 16 permits the switch 242 to open, producing no immediate effect, but serving to preclude subsequent advance of the slide and clamp assembly 15 until the saw assembly 16 is again in its retracted position. It is, therefore, apparent that the slide and clamp assembly may be advanced only when both the saw assembly 16 and the welder are in their respective retracted positions.

Completion of the above-mentioned circuit through the contacts 268 of the relay 265 and through the unlatching coil 273 of the relay 270 produces an effect to be described hereinafter.

20 As soon as the desired length of finished tube has been severed from its parent stock, the switch 244 will obviously resume its normally open position, thus deenergizing the coil 261 of the relay 260 and permitting the contacts 262 and 263 to open. Opening of the contacts 262 in turn deenergizes the coil 256 of the relay 255, thus causing the contacts 257 and 258 to open and results finally in deenergizing both the unlatching coil 254 of the relay 250 and the welder circuit.

25 As before, however, the relay 250 is already in its normal position and the welding cycle is unaffected by opening of the welder circuit.

Opening of the contacts 263, of course, deenergizes the actuating coil 266 of the relay 265, but the now closed contacts 267 and 268 are not affected due to their being mechanically latched in closed position, in which position they will remain until subsequent energization of an unlatching coil 269 of the relay 265.

30 40 Arrival of the saw assembly 16 at the advanced end of its travel closes the switch 243 to complete a circuit through a coil 276 of a two pole, single throw, normally open relay 275. This results in closing normally open contacts 277 and 278, the latter of which completes a circuit through the above-mentioned unlatching coil 269 of the relay 265 and causes the contacts 267 and 268 to open. Opening of the contacts 267 deenergizes the "advance" side of the valve 215, while opening of the contacts 268 deenergizes the unlatching coil 273 of the relay 270, this coil 273 having by this time produced an effect hereinafter to be described.

45 50 Closing of the contacts 277 completes a circuit through an actuating coil 271 of the relay 270, thus causing normally open contacts 272 to close and to complete a circuit through the "retract" side of the valve 215. The saw assembly 16 is thus caused to retract from its advanced position whereupon the switch 243 is again opened. This causes the coil 276 of the relay 275 to be de-

60 65 energized and the contacts 277 and 278 to open. Opening of the contacts 277 deenergizes the actuating coil 271 of the relay 270, but the now closed contacts 272 are not affected due to their being mechanically latched in closed position, which condition will obtain until the unlatching coil 273 is again energized during a subsequent cycle of events as above-described. Opening of the contacts 278 deenergizes the unlatching coil 269 of the relay 265, this coil 269 having already effected the return of the contacts 267 and 268 to their normally open condition.

70 75 Arrival of the saw assembly 16 at the retracted end of its travel again closes the switch 242. If, at this point, the last instigated welding cycle has

been completed so that the switch 240 is in closed position, it is obvious that the contacts 253 of the relay 250 will also be in closed position and that closing of the switch 242 will again complete a circuit through the "advance" side of the valve 214 to again start the sequence of operations above described. If, on the other hand, closing of the switch 242 occurs before the last instigated welding cycle is completed, energization of the "advance" side of the valve 214 will be delayed until the switch 240 closes to energize the actuating coil 251 and close the contacts 253 of the relay 250.

It will be noted that, as this second sequence of operations is begun, the conditions of the electrical circuits of Fig. 15 are similar to those which obtained at the beginning of the first described sequence except that the contacts 272 of the relay 270 are latched in closed position, thereby causing the "retract" side of the valve 215 to remain energized. These contacts 272 will open, however, when the unlatching coil 273 of the relay 270 is energized as above described. It is thus apparent that the "retract" side of the valve 215 remains energized at all times during which advance of the saw assembly 16 would be particularly detrimental to the desired operation of the wire cloth tube forming machine 10.

The above-described machine, which is capable of forming a tube from an appropriate strip of wire cloth, of cooperating with a conventional welder to effect welding of the overlapped edges of the wire cloth thus formed into a tube, and of cutting off portions of the tube to desired lengths, obviously fulfills the objects and advantages sought therefor. It is to be understood that the foregoing description and the accompanying drawings have been given by way of illustration and example. It is also to be understood that changes in the form of the elements, rearrangement of parts, and substitution of equivalent elements, which will be obvious to those skilled in the art, are contemplated as within the scope of the present invention which is limited only by the claims which follow.

What is claimed is:

1. In a wire cloth tube forming machine, an electrode assembly comprising a welding electrode having a cylindrical portion and a flared portion, said electrode having a straight longitudinal bore formed concentrically with said cylindrical portion and extending through said flared portion, an adapter connected to said flared portion, a tube connected within said adapter and extending therefrom in spaced concentricity with said bore through said flared portion and into said cylindrical portion, means to admit a liquid to said adapter, and means to exhaust a liquid from said adapter, there being a path for flow of liquid from said means for admittance, through said tube, and thereafter within said bore externally of said tube to said means for exhausting the liquid.

2. In a wire cloth tube forming machine, in combination, a former assembly and a welding electrode, said former assembly comprising a body having an internal bore, said bore including a cylindrical portion and a flared portion, said welding electrode being received in said bore and having an external configuration similar thereto, a uniform annular space between said bore and said electrode, a slot in said body parallel to said bore, said slot communicating with said bore to provide access of a second welding electrode to a portion of said annular space, and

means to retain said body and said first-mentioned electrode in fixed relative positions.

3. In a wire cloth tube forming machine, means for advancing a wire cloth tube comprising a tube guide extension rod extending coaxially from a cylindrical portion of a welding electrode, a sleeve slidably mounted on said rod, a spring biasing said sleeve toward said electrode, and a slide and clamp assembly adapted first to embrace a portion of said sleeve so as to effect a clamping action thereupon and thereafter to move said sleeve in a direction away from said electrode.

4. In a wire cloth tube forming machine, means intermittently to advance a wire cloth tube comprising a sleeve about which a portion of a tube may be slidably disposed, a rod upon which said sleeve is slidable, resilient means biasing said sleeve toward one end of said rod, a plurality of clamping assemblies each having a clamping element reciprocable normal to said sleeve whereby portions of a tube may be alternately clamped to and released from said sleeve, means to reciprocate said plurality of clamping assemblies parallel to said sleeve whereby said sleeve and a tube clamped thereto may both be advanced in a direction against the biasing action of said resilient means, and means to coordinate said clamping action and the release thereof with said reciprocation of the clamping assemblies whereby said clamping action may be instigated before, and maintained during the movement of said clamping assemblies in said direction of advance and whereby said releasing action may be instigated before, and maintained during the movement of said clamping assemblies opposite to said direction of advance.

5. In a wire cloth tube forming machine, a slide and clamp assembly comprising a carrier, power operated means for reciprocating the carrier, and a pair of clamping assemblies mounted on the carrier so as to be movable therewith, said clamping assemblies being in opposed relation one with the other, each including a power operated reciprocable resilient cushion adapted to engage a portion of a wire cloth tube disposed on a cylindrical sleeve.

6. In a wire cloth tube forming machine, a slide and clamp assembly comprising a carrier, a double-acting cylinder assembly connected to said carrier for reciprocation thereof, a pair of clamping assemblies mounted on said carrier so as to be movable therewith, each clamping assembly including a movable clamping element and a single acting spring return cylinder assembly connected thereto, means for delivering power from a single source to one end of said double-acting cylinder and to each of said single acting cylinder assemblies including means to delay said delivery to said end of said double-acting cylinder assembly until substantially after delivery to each of said single acting cylinder assemblies to provide for a desired sequential operation of said slide and clamp assembly in one mode of movement, and means associated with said delivery means for a quick release of power from said single acting cylinder assemblies to provide for a second desired sequential operation of said slide and clamp assembly in another mode of movement.

7. In a wire cloth tube forming machine, means for severing a wire cloth tube into segments of predetermined length comprising stationary means to support a tube from the interior thereof, means to advance a segment of a tube beyond said stationary supporting means, a movable cut-

ting blade to sever a segment from a tube, and stationary means adapted to support a tube including a segment externally thereof during a severing operation, said latter means including a stationary arcuate element disposed on each side of the plane of said cutting blade.

8. In a wire cloth tube forming machine, means for severing a wire cloth tube into segments of predetermined length comprising means to support a tube from the interior thereof, power operated means for intermittently advancing a supported tube so as to cause a predetermined length thereof to extend beyond said supporting means, control means cooperating with said power operated means to prevent further advance of a tube as long as a predetermined length thereof extends beyond said supporting means, a power operated reciprocable cutting blade adapted to sever a segment of predetermined length from a tube, control means cooperating with said reciprocable cutting blade whereby a segment is severed from a tube only when a predetermined length thereof has been advanced beyond said supporting means, arcuate shaped means externally of a tube for supporting both the tube and a segment being severed therefrom, and control means whereby the advance of a tube is resumed subsequent to a severing operation.

9. In a wire cloth tube forming machine comprising means to advance a continuous strip of wire cloth through a forming assembly wherein the edges of said strip are overlapped, means adapted to cooperate with conventional welding means for seam-welding overlapped edges of a tube to produce a seam-welded tube, and means for severing predetermined lengths from a seam-welded tube, in combination, a first power operated means to actuate said advancing means, a first electrically operable control associated with said first power means, a second power operated means to actuate said severing means, a second electrically operable control associated with said second power means, and an arrangement of electrical circuits cooperating with said first and second electrically operable means to effect a desired sequential operation of said advancing means, said welding means including said means cooperative therewith, and said severing means, thereby to provide for continuous automatic operation of said wire cloth tube forming machine.

10. In a wire cloth tube forming machine comprising means to advance a continuous strip of wire cloth through a forming assembly wherein the edges of the strip are overlapped, means adapted to cooperate with conventional welding means for seam-welding overlapped edges of a tube to produce a seam-welded tube, and means for severing predetermined lengths from a seam-welded tube, in combination, a first power operated means to actuate said advancing means, a first electrically operable control associated with said first power means, a second power operated means to actuate said severing means, a second electrically operable control associated with said second power means, and an arrangement of electric circuit elements cooperating electrically with said first and second electrically operable means and with said conventional welding means and cooperating mechanically with said advancing means, with said conventional welding means, with said severing means, and with a seam-welded tube to effect a desired sequential operation of said advancing means, said welding means including said means cooperative therewith, and said severing means, thereby to provide for con-

tinuous automatic operation of said wire cloth tube forming machine.

11. A method for transforming a continuous strip of wire cloth into tubular segments of predetermined length comprising the steps of alternately overlapping the edges of a previously determined length of the continuous strip to form a previously determined length of tube and bonding an equal previously determined length of overlapped edges to produce a continuous bonded tube, interrupting the production of continuous bonded tube when predetermined lengths thereof have been produced and severing tubular segments of desired predetermined length from the bonded tube during the interruption in production.

12. A method for transforming a continuous strip of wire cloth into tubular segments of predetermined length comprising the steps of advancing the continuous strip longitudinally through a forming assembly adapted to overlap the edges thereof to form a tube, retaining the thus formed tube in the forming assembly and supporting the overlapped edges from the interior of the tube, bonding the overlapped edges while they are thus supported in the forming assembly, advancing the bonded tube beyond the forming assembly, and severing tubular segments of desired predetermined length from the bonded tube.

13. A method for transforming a continuous strip of wire cloth into tubular segments of predetermined length comprising the steps of intermittently advancing the continuous strip longitudinally through a forming assembly adapted to overlap successive portions of the edges thereof to form a portion of a continuous tube during each intermittent advance, bonding successive portions of the overlapped edges while the tube is held stationary between intermittent periods of advance, interrupting the intermittent advancement of the tube when a predetermined length thereof has been bonded, severing a tubular segment of desired predetermined length from the bonded tube during the period of interrupted intermittent advancement, and repeating the above cycle.

14. A wire cloth tube forming machine comprising, in combination, stationary forming means including a stationary welding electrode for receiving a continuous strip of wire cloth and overlapping the edges of the same, a reciprocable welding electrode cooperative with said forming means and said welding electrode therein for bonding the overlapped edges of wire cloth, means for advancing the wire cloth through the forming means, means for reciprocating the reciprocable welding electrode, and means for coordinating the advance of the wire cloth with the reciprocation of the reciprocable electrode, whereby to produce a continuous wire cloth tube having a rectilinear welded seam.

15. The combination of claim 14 wherein the means for advancing the wire cloth is intermittently operable, and wherein the means for coordinating the advance of the wire cloth with the reciprocation of the reciprocable electrode is adapted to effect alternate advancing movements of the wire cloth and reciprocations of the reciprocable electrode.

16. A wire cloth tube forming machine comprising, in combination, means for receiving a continuous strip of wire cloth, means for advancing a strip of wire cloth by intermittent stages longitudinally through said receiving means, means in said receiving means for overlapping

15

the edges of a strip of wire cloth during longitudinal advance thereof through said receiving means, means in said receiving means adapted to cooperate with conventional welding means to seam-weld overlapping edges of a strip of wire cloth to produce a seam-welded tube, means for severing predetermined lengths from a seam-welded tube, and means for automatically controlling said advancing means, said welding means, and said severing means automatically to produce a plurality of wire cloth tubes from a strip of wire cloth.
